US0D1108884S

(12) **United States Design Patent** (10) Patent No.: **US D1,108,884 S**
(45) Date of Patent: ** Jan. 13, 2026

(54) **PART OF COOKING PAN**

(71) Applicant: **NeoStove B.V.**, Delft (NL)

(72) Inventors: **Surya Prakash Seshaiya Doraiswamy**
Chandrasekar, Delft (NL); **Wytze**
Anne De Vries, Delft (NL)

(**) Term: **15 Years**

(21) Appl. No.: **35/522,129**

(22) Filed: **May 29, 2024**

(80) **Hague Agreement Data**

Int. Filing Date: **May 29, 2024**

Int. Reg. No.: **DM/239387**

Int. Reg. Date: **May 29, 2024**

Int. Reg. Pub. Date: **Aug. 30, 2024**

(30) **Foreign Application Priority Data**

Dec. 8, 2023 (EM) 015043795-0001
Dec. 8, 2023 (EM) 015043795-0002

(51) **LOC (15) Cl.** **07-02**

(52) **U.S. Cl.**

USPC **D7/402**
